(57) **CLAIM**

The ornamental design for a portable speaker system with media player dock and alarm clock, as shown and described.

DESCRIPTION

FIG. 1 is a top, front, right side, perspective view of a portable speaker system with media player dock and alarm clock in a closed condition showing my new design;

FIG. 2 is a front view thereof;

FIG. 3 is a rear view thereof;

FIG. 4 is a top view thereof;
FIG. 5 is a side view thereof, the opposite view being a mirror image;

FIG. 6 is a bottom view, thereof;

FIG. 7 is a cross sectional view thereof along the line 7—7 in FIG. 4;

FIG. 8 is a top, front, right side, perspective view thereof in an open condition;

FIG. 9 is a front view thereof;

FIG. 10 is a top view thereof;

FIG. 11 is a rear view thereof; and,

FIG. 12 is a side view thereof, the opposite view being a mirror image.

The broken line showing is of environmental material and forms no part of the claimed design.
